UTILITY PURSE

Harry I. Thomas, Hagerstown, Md., assignor to
The Hagerstown Leather Company, Hagerstown, Md., a corporation of Maryland

Application September 4, 1951, Serial No. 16,495

Term of patent 7 years

(Cl. D87—3)

To all whom it may concern:

Be it known that I, Harry I. Thomas, a citizen of the United States of America, residing at Hagerstown, in the county of Washington and State of Maryland, have invented a new, original, and ornamental Design for a Utility Purse, of which the following is a specification, reference being had to the accompanying drawings, forming part hereof.

In the drawings, Fig. 1 is a perspective view showing one side of the utility purse of the invention, Fig. 2 is a similar view showing the opposite side thereof, Fig. 3 is an elevational view of the inside purse illustrating the several elements thereof in closed condition, Fig. 4 is a view similar to Fig. 3, but illustrating the several elements in open condition, Fig. 5 is an elevational view of the pass case element in opened condition, Fig. 6 is a side elevation of the purse showing the outer strap member with its snap fastener engaged in a manner similar to that shown in Fig. 2, and Fig. 7 is a view similar to Fig. 6 but showing the snap fastener of the outer strap member disengaged and the strap member in raised position.

I claim:

The ornamental design for a utility purse, as shown and described.

HARRY I. THOMAS.
